ELEVATOR

William E. Hastings, Jetmore, Kans.

Application March 11, 1930. Serial No. 434,839

9 Claims. (Cl. 187—1)

This invention relates to improvements in elevators and it consists of the constructions, combinations and arrangements herein described and claimed.

5 One of the foremost objects of the invention is to provide an elevator which is made in sections that can be coupled in a variety of ways thus to adapt the elevator to the various locations of stalls in a building or garage especially designed 10 for the combined use therewith of this elevator, into which stalls it is proposed to move automobiles or other vehicles carried by the elevator.

Another object of the invention is to provide 15 an elevator equipped with movable conveyors by the use of which an automobile hoisted by the elevator can be propelled off and into a stall arranged to receive it.

A further object of the invention is to make an 20 elevator in a plurality of sections, each being equipped with a set of movable conveyors, there being provision for coupling pairs of the sections so that an automobile may be elevated in any 25 one of a number of lateral positions, both the position of an automobile and the selection of sections to be coupled depending on the location of the stall into which it is desired to move the automobile.

A still further object of the invention is to provide 30 a novel suspension for the elevator, this including means by which the suspension cables can be fitted to any selected plurality of elevator sections so that the hoisting pull may be directly over those sections and not diverted to one side.

Other objects and advantages will appear in 35 the following specification, reference being had to the accompanying drawings in which

Figure 1 is a side elevation, partially in section, illustrating the general arrangement of the improved elevator.

40 Figure 2 is a detail section of the main bearing of the wheel which forms part of the elevator suspension.

Figure 3 is a diagrammatic plan view illustrating 45 the sectional elevator and the movable conveyors of the sections as well as the relationship of the elevator to a specially constructed garage.

Figure 4 is a plan view, partially in section, of a 50 modification showing the elevator in one piece but adopting the same arrangement of movable conveyors for a garage of the preceding design.

Figure 5 is a plan view of the clutch and motor controls of one of the elevator sections, the cover being shown in section.

55 Figure 6 is a plan view of one of the elevator sec-

tions showing the movable conveyors in more detail.

Figure 7 is a cross section taken substantially on the line 7—7 of Figure 6.

Figure 8 is a cross section at right angles to 80 Figure 7, taken on the line 8—8 of Figure 6.

Figure 9 is a detail view of one of the drag winches of which several are carried by each elevator section, the view being taken substantially on the line 9—9 of Figure 6. 85

Figure 10 is a plan view of the elevator suspension, also illustrating the elevator in its regular position therebeneath.

Figure 11 is a diagram of the electrical wiring.

Figure 12 is a diagram somewhat on the orders 70 of Figures 3 and 4, illustrating a fractional elevator which is adapted to distribute automobiles in only two directions rather than in four directions.

Figure 13 is a detail plan view of the coupling 75 means by which the sections are joined.

Figure 14 is a detail view of one of the automobile stops, parts of the platform being shown in section.

Figure 15 is a detail sectional view of a portion 80 of the wheel of the shaft particularly showing one of the supporting rollers.

Figure 16 is a detail sectional view illustrating the quadruplex guide rail.

The elevator herein disclosed is directly concerned 85 with the problem of conveniently and speedily parking automobiles in a garage especially designed for the purpose. Although the description is devoted to this particular use, it is intended that the elevator shall be adaptable to 90 other uses because it is capable of being employed in any connection where it is a consideration to store objects in vertical series of stalls arranged in various lateral directions.

It will presently be understood that the elevator 95 is intended to replace ramps such as are now popularly used in connection with public garages, it being a premise inseparable with the principle of the invention that an automobile can be parked in a stall twenty-five stories above street level in an equal and perhaps smaller period of time than would be required in parking the same vehicle on the first or second floor of the average garage of the type mentioned.

With the general purpose in mind attention is 100 directed to the drawings so that the principles can be understood. The elevator, generally designated 1, (Figure 3, 4 and 12), is capable of being made in a variety of ways as these views indicate. In Figure 3 it is composed of four sections 2, 3, 110

4 and 5. These are inherently separate but are not used separately in the raising and lowering of an automobile A (Fig. 3).

They are intended to be coupled in pairs by means 6 (Fig. 13) which, for the purpose of the simplest illustration, comprises slide bolts 7 and keepers 8. The arrangement of this means may be according to any way one might choose to make it, the idea being to enable coupling any two of 10 the sections so as to compose a single elongated elevator substantially of the shape of the automobile which it is intended to transport.

For example if the automobile A (Fig. 3) is to be housed either east or west the sections 2, 3 or 15 4, 5 would be coupled laterally in east and west directions. On the other hand, should it be intended to park the automobile north or south, sections 2, 4 or 3, 5 would be correspondingly coupled to compose elongated units.

20 A second mode of making the elevator is to omit the sectional construction and make it in one piece as in Figure 4. The sectional construction is also omitted in Figure 12 and while the elevator 1 is herein made in one piece yet that piece 25 is merely an elongated unit, such as either east or west pair (Fig. 3) might comprise, the intention being to confine the use of this particular elevator to extremely narrow buildings for localities where there may either be a restriction 30 of ground space or a merely normal demand for elevated parking space.

In any case the elevator will be equipped with sets of movable conveyors 9 arranged to run only in opposite directions. This is true of the respective forms in Figures 3, 4 and 12, but since the elevators of Figures 3 and 4 are intended for use in a building of more than two stall wings they are further equipped with sets of movable conveyors 10 capable of running in opposite directions at right angles.

This leads to a consideration of the types of buildings in which the elevator 1 will be employed. According to Figures 3 and 4 the building 11 will be equipped with east and west wings 12, 13, also 45 north and south wings 14, 15. These wings are substantially as high as the building and will be horizontally divided into as many floors or stories as it is intended to erect the building. Each horizontal floor is divided by partitions 16 to provide 50 pairs of stalls 17. The automobile A can be propelled into any one of the eight stalls on a single floor, and the use of a given set of the movable conveyors depends upon the selected stall.

In Figure 12 the building 11 is very narrow. It 55 is built with opposite wings 18, 19 which, evidently represent single stalls on the various floors. The selection of the parking space on each floor is confined to one or the other stall and not to any one of four pairs of stalls as in Figures 3 60 and 4.

The manner in which the right angularly disposed sets of conveyors 9, 10 are driven is as follows: The immediately following description is confined to the conveyors of the elevator section 65 2 (Fig. 6), the mode of driving any other group of conveyors either in Figures 3 and 4 being identical. Shafts 23, 21 (Fig. 6) carry sprockets 22 to which the conveyors are applied. The conveyors comprise linked chains of the Morse silent 70 drive type. Their purpose is to propel an automobile off of the elevator and into one of the stalls 17, to which end the wheels of the automobile will ride upon those of the conveyors that are aligned in one direction.

75 For example, the conveyors in the series 9 are

so arranged that one begins where another ends, and although this makes a staggered arrangement there will, nevertheless, be a continuous driving effort when the conveyors are set in motion. The operator would start the conveyors 9 of the section 2 then step over to the section 3 and start the corresponding conveyors 9. The automobile would thus be propelled into the position A (Fig. 3). Other sets of conveyors would be similarly manipulated.

80 A single shaft 23 (Figs. 6 and 8) is the common drive of the conveyors 10, the near ends of these being applied to sprockets 24 on the shaft (Fig. 8), while the remote ends are applied to similar sprockets on shafts 25. A motor 26 (Fig. 7) is 85 the source of power for either set of conveyors 9, 10.

This motor is mounted on a base 27 that is suspended from the platform 28 of the section 2 in any suitable manner. Brackets 29 may be used 90 for the purpose, these spacing the base from the platform to provide a chamber by which the driving mechanism is housed (Figs. 7 and 8).

95 A chain 30 (Fig. 7) from the motor 26 drives a counter shaft 31 which, by means of a chain 32 100 drives a primary clutch shaft 33. A clutch 34, splined to the shaft 33 controls the forward and reverse motion of either set of conveyors 9, 10. It is engageable with either clutch element 35, 36, each of which is loose on the shaft 33 and respectively connected by straight and crossed belts or chains 37, 38 with a driven shaft 39. The various chains or belts are obviously applied to sprockets although these are not specifically mentioned in either the foregoing or following description.

110 A chain 40 (Fig. 7) drives a main shaft 41 from the driven shaft 39. The main shaft carries loose clutch elements 42, 43 with either of which a clutch 44 splined on the main shaft is engageable. When engaging the element 42 driving power will be transmitted through a chain 45 to a shaft 46 from which both conveyors 9 are simultaneously driven by chains 47.

115 When the clutch 44 is engaged with the element 43, driving power will be applied through a train of gearing 48 as well as sprocket chains 49 to the single shaft 23 previously mentioned, which is the common driver of the conveyors 10.

Levers 50 and 51 (Fig. 6) movable in slots 52, 125 53 of a control panel 54 (Fig. 5) control the clutches 34, 44 through respective articulated connections 55, 56 (Fig. 6). Forward and reverse driving of the conveyors 9, 10 is accomplished by moving the lever 50 into either end of the slot 52 130 either by hand or foot, while the selection for driving either conveyors 9 or 10 is made by moving the lever 51 to either end of the slot 53 by hand or by foot.

A hinged cover 57 (Figs. 5 and 6) protects the 135 clutch levers 50 and 51 as well as a switch 58 by which the running of the motor 26 is controlled. The cover 57 will be raised to reach any of the members mentioned. This cover serves the important purposes of excluding dirt and preventing the accidental throwing of either the clutch levers or switch.

140 It is intended that the automobile shall be pulled on to the elevator and not propelled by its own power, and the means by which this is accomplished is as follows: The outer shaft 20 of one of the conveyors 9 (Fig. 6), as well as the outer shaft 25 of one of the conveyors 10, is sufficiently extended at 59 (Fig. 9) to carry a drag winch 60. One end of this carries a clutch ele- 145

ment 61 which is engageable by a slidable and splined clutch 62 that is movable by a short lever 63. A cable 64 is wound on the winch, one end being secured thereto and the other end having a hook 65 adapted to be attached to some convenient part of the automobile.

For the purpose of preventing the automobile from rolling off of the elevator during vertical transportation the platform 28 is equipped with 10 stops 66 (Fig. 14). Each of these is hinged at 67 so that it can be raised or lowered in respect to an opening 68 in which it fits in the platform. A chain 69 limits the opening movement of the stop. When needed no longer the stop can simply be 15 kicked over whereupon it will lie flush with the top surface of the platform.

The suspension of the elevator and the means by which it is applied to any coupled pair of the sections (Fig. 3) is as follows: Situated on the 20 nether part of an appropriate framework 70 at the top of the elevator shaft 71 (Fig. 1) is a large wheel 72 that is revolvably supported by a central thrust bearing 73 (Fig. 2). It has additional peripheral supports (Fig. 15) which comprise rollers 74, or preferred equivalents, on which the nether rim of the wheel bears.

A heavy sheave 75 (Fig. 1) is swivelly suspended from an eye 76 on the wheel 72. A hoisting cable 77, trained through this sheave and over 30 guides 78 terminates at one end in a hanger arrangement 79 within the elevator shaft, and at the other end in a hoisting drum 80 at the bottom of the shaft.

The drum is driven by a motor 81 that is controlled from the elevator by a reversing switch 82. This switch is also housed under the cover 57 (Fig. 5). Upon throwing the switch 82 in one position the elevator will be raised, and upon throwing it in the other position the elevator will 40 be lowered.

The hanger arrangement 79, to which reference has been made, comprises chains or cables arranged in the approximate manner indicated in Figures 1 and 10. The hanger members end in 45 hooks 83 which will be fitted in the heavy eye bolts 84 at the four corners of each section. The hanger arrangement may be regarded as a harness that is capable of being attached to any selected pair of elevator sections, for which purpose the 50 sections would first have to be let down into resting positions upon beams 85 at the bottom of the shaft (Fig. 1) so that the harness can be unhooked and re-applied to the selected couple.

A motor 86 has a drive connection with the 55 wheel 72 through the medium of a counter shaft 87 (Fig. 1) to the opposite ends of which a chain 88 and gear shaft 89 are applied by means of a requisite sprocket and bevelled gearing. The lower end of the shaft 89 carries a spur gear 90 which meshes with the gear periphery 91 of the wheel 72 (Fig. 10).

This gear periphery may extend completely around the circumference of the wheel or only half-way around depending on whether it is proposed to employ but a single hoisting cable 77 for all of the connectible elevator sections or couples. In the instance of the complete gear periphery the wheel 72 would be rotated in quarter turns to center the sheave 75 over any connected pair of 70 elevator sections.

For example, Figure 10 shows the sheave 75 centered over the sections 2, 4, it being presumed that these are the connected pair. Should the sections 2, 3 be connected, the wheel would be given a quarter turn in the clockwise direction

to center the sheave over that pair. Or should it be desired to elevate the sections 3, 5 the wheel would be given a half turn in the clockwise direction to appropriately center the sheave 75.

Under the foregoing condition only one selected pair of elevator sections can be operated at a time. It is possible to operate two pairs separately. This would require a duplication of the cable 77 as well as the hoisting drum 80 on the other side of the shaft. For this purpose the wheel 72 is equipped with an extra eye 92 (Fig. 2) from which a duplicate sheave 75 would be swivelly suspended. Only a half gear periphery 91 would be necessary since fractional turns in either direction would center the two sheaves over the separately coupled and independently operable elevator units.

A reversing switch 93, preferably located somewhere near the bottom of the elevator shaft controls the circuit of the motor 86 so that the motor may be operated in either direction to appropriately turn the wheel 72 as may be required. Appropriate rails 94 (Fig. 6) are provided to guide the elevator sections regardless of the unit formation in which they might be coupled. While the arrangement of the guide rails will be subject to some variation yet the illustration in Figure 3 shows a fair distribution.

Here single guide rails 94 are situated at the four corners of the elevator shaft 71 while a quadruplex guide rail 95 (Fig. 16) is shown in the center of the shaft. It follows that any elongated unit of connected sections will have adequate guidance at three points.

The electrical wiring is diagrammatically illustrated in Figure 11. Since the motors 26, single-point switches 58 and reversing switches 82 are all alike in respect to each of the four sections they are given the common and corresponding designations indicated. The motors 26 and switches 58 are connected in parallel couples by means of wires 96, 97 and 98, 99 which in turn are connected in parallel with feeders 100, 101 from busses 102, 103. These features also constitute the positive and negative current sources for the reversing switches 82 which are connected 110 in parallel by means of wires 104, 105 and 106, 107. The various wires are connected to the feeders 100, 101 as plainly indicated.

The elevator motor 81 is connected with each of the reversing switches 82 by wires 108, 109 which connect either directly to corresponding contacts of certain reversing switches or have branches leading thereto so that all corresponding contacts are connected with appropriate sides of the lines. The busses 102, 103 are therefore 125 the source of current for all of the motors it being observed that two terminals of the reversing switch 93, identified with the motor 86, are also connected with these busses.

The operation

is readily understood. All forms of the invention are adapted to the allocation of automobiles in a garage with wings provided with stalls to receive them. Consider the arrangement in Figure 13. The sections 2, 3 had been coupled through the medium of the coupling means (Fig. 13) to receive the automobile A. They were hoisted to the desired story of the garage or building 11 by turning the wheel 72 (Fig. 10) 90 degrees in the clockwise direction from the position there shown.

This brought the sheave 75 directly over the coupled sections 2, 3. The hooks 83 of the harness 79 were fitted in the eye bolts 84 so as to sup-

port the sections. The automobile A was dragged on to the coupled sections 2, 3 by setting the aligned movable conveyors 9 of both sections in motion and clutching in an appropriate one of 5 the drag winches 60 (Figs. 6 and 9) so as to start the automobile on to the now moving conveyors 9 after having connected the hook 65 of the cable 64 to a convenient part of the vehicle.

Having gotten the automobile on to the elongated unit 2, 3, the wheels will stand on the remote conveyors 9. The clutches 44 (Fig. 7) of each section 2, 3, previously engaged with the elements 42 by means of the levers 51 (Fig. 6) are now restored to the neutral position (Fig. 7) 15 so that the conveyors 9 stand still while the automobile is being elevated. Appropriate stops 63 are raised to prevent the automobile from rolling off.

The circuit 108, 109 (Fig. 11) of the motor 81 20 (Fig. 1) is closed by throwing the reversing switch 82 of either section 2, 3 in the proper direction to raise the elevator. Having reached the desired level the operator will unhook the automobile from the winch 60, start the motors 26 of the 25 sections 2, 3 by closing the switches 58 and move the levers 51 so as to re-engage the clutches 44 with the elevators 42. However, it is necessary to move the levers 50 to reverse the former main shaft 41, thus causing the conveyors 9 to propel 30 the automobile off of the elevator and into the position which it is shown as occupying in one of the stalls 17 (Fig. 3).

In the instance of the single piece elevator in Figure 4 the operator has only to control the desired sets of conveyors 9, 10 in order to move the automobile on or off of the platform. There is no need for the specific suspension means of Figures 1 and 10, the ordinary elevator hoisting mechanism being sufficient to serve the purpose.

40 This is also true of the arrangement in Figure 12, but as previously pointed out the elevator 1 is confined to a single elongated unit which one might consider as the permanent assemblage or connection of a pair, for example 2, 3 of the section in Figure 3. Only single sets of conveyors 9 will be used since the requirement is to move the automobile either east or west into the opposite wings 18, 19. These constitute single stalls.

While the construction and arrangement of the 50 improved elevator is that of a generally preferred form, obviously modifications and changes may be made without departing from the spirit of the invention or the scope of the claims.

I claim:—

55 1. In an elevator, a plurality of floor sections, an elevator shaft and means for guiding said sections therein, and means for coupling selected sections to constitute a unit variously allocated in said shaft.

30 2. An elevator comprising a plurality of floor sections, an elevator shaft and means for guiding said sections therein, means for coupling selected sections to constitute a unit variously allocated in said shaft, suspension means common to any 55 unit, and a carrier for the suspension means being shiftable with respect to the shaft in accordance with the selection of the sections thus to be centered over the unit.

3. An elevator comprising a plurality of floor

sections, an elevator shaft and means for guiding said sections therein, means for coupling selected sections to constitute a unit, a cable including a portion suspended in the shaft and terminating in a harness applicable to the unit, and supporting means for centering the suspended portion and harness over the unit.

4. An elevator comprising a plurality of floor sections, an elevator shaft and means for guiding said sections therein, means for coupling selected sections to compose a unit, a cable having a harness applicable to the unit, movable means carrying a sheave from which the cable is suspended in said shaft, and means to move said movable means in accordance with the selection of the sections thus to center the suspended cable and harness over the unit.

5. An elevator comprising a plurality of floor sections, means for selectively coupling the sections to compose a unit, a shaft in which the elevator is movable, a cable by which it is moved having a harness applicable to the unit, a wheel mounted on the top of the shaft having a sheave from which the cable is suspended, and means to turn the wheel thus to center the suspension of the cable over the unit.

6. An elevator comprising a plurality of floor sections, a shaft traversible by the elevator, means for coupling selected sections to compose an elevator unit, and rails disposed in the shaft to guide plural portions of the unit regardless of which sections are coupled to compose it.

7. An elevator comprising a plurality of floor sections, a shaft traversible by the elevator, means for coupling selected sections to compose an elevator unit, and rails along the corners and the center of the shaft for guiding the unit regardless of which sections are coupled to compose it.

8. An elevator comprising a shaft, a wheel, a sectional floor situated in the shaft and means for coupling the floor sections in pairs to compose a unit, guide means in the shaft with which all of the floor sections have guiding engagement both singly and when coupled in unit form, a hoisting cable depending from the substantial periphery of the wheel for moving said unit vertically, a harness carried by the cable and means for attaching the harness to said unit, and means on which the wheel is turnable to dispose the harness over said unit, said means supporting the wheel horizontally within the confines of the shaft.

9. An elevator comprising a shaft, a wheel, a sectional floor situated within the shaft and means for coupling certain floor sections in pairs to constitute a unit, guide means in the shaft with which all of the floor sections have guiding engagement both singly and when coupled in unit form, means for moving said unit vertically comprising a hoisting drum and a cable, a sheave at the substantial periphery of the wheel over which a portion of the cable is trained, a harness carried by said portion of the cable having means for its attachment with said unit, and means for supporting the wheel horizontally and turnably within the confines of the shaft to enable centering the harness over the unit.

WILLIAM E. HASTINGS.
